UNITED STATES PATENT OFFICE.

ORIN ACKLEY, OF NEW ALBANY, PENNSYLVANIA.

DESIGN FOR A SPIKE-HOLE PLUG.

SPECIFICATION forming part of Design No. 28,851, dated June 14, 1898.

Application filed May 12, 1898. Serial No. 680,522. Term of patent 3½ years.

To all whom it may concern:

Be it known that I, ORIN ACKLEY, a citizen of the United States, residing at New Albany, in the county of Bradford and State of Pennsylvania, have invented a new and original Design for Spike-Hole Plugs, of which the following is a specification.

My invention relates to designs in spike-hole plugs, which is fully illustrated in the accompanying drawings, of which—

Figure 1 is a front perspective view. Fig. 2 is a rear perspective view. Fig. 3 is a cross-sectional view taken on the line 3 3 of Fig. 1.

My design consists of an elongated rectangular stem portion *a*, having one end rounded, as shown at *b*, the said rounded end terminat-

ing in the abrupt circular extremity *c*. It will be noted that at the junction of the tapered or rounded portion *b* the curved lines *d* are formed.

Having thus described my invention, what I claim, and desire to secure by Letters Patent, is—

The design for a spike-hole plug substantially as herein shown and described.

In testimony whereof I have hereunto set my hand in the presence of two subscribing witnesses.

ORIN ACKLEY.
